UNITED STATES PATENT OFFICE

EDMUND C. MORGAN, DECEASED, LATE OF NEW YORK, N. Y., BY OLIVE EUGENIE MORGAN, EXECUTRIX, OF NEW YORK, N. Y.

LOADING MACHINE

Application filed January 26, 1925, Serial No. 4,763. Renewed August 26, 1929.

This invention relates to loading machines and one of the objects thereof is the provision of improved and efficient apparatus of this type. The present application is a continuation in part of the copending application of said Edmund C. Morgan, Serial No. 346,903, filed December 23, 1919, for an Improvement in mining and loading apparatus.

More particularly it is the object of the present invention to provide improved loading apparatus comprising mechanism for gathering dislodged material from the mine floor by an arcuate sweep across the same, load the dislodged material into a deep hopper from which such material may be loaded in various directions into mine cars.

Other objects of the invention will appear hereinafter, the novel combinations and features being set forth in the appended claims.

Referring to the accompanying drawings, Fig. 1 is a plan view of the loading machine combined with mining mechanism.

Fig. 2 is an elevational view of the combined mining and loading machine with a portion of the kerf cutting mechanism included to show its relation to the other parts;

Fig. 3 is an enlarged elevational view, partly in section, of the coal splitting mechanism shown at the right hand portion of Fig. 2, and also of the mechanism for swinging the gathering conveyer;

Fig. 4 is an enlarged view, partly in section, of the right hand portion of Fig. 2, but looking on the left toward the right;

Fig. 5 is a sectional detail view of the three-way valves particularly adapted for use in the control system of pressure pipes shown in Figs. 1 and 2;

Fig. 6 is a sectional elevation of the forward swinging conveyer and of the mechanism for delivering coal to said conveyers;

Fig. 7 is a plan view of the structure shown in Fig. 6;

Fig. 8 is a plan view of modified mechanism for swinging the coal splitting mechanism with sufficient force to operate the latter, such swinging mechanism being capable of returning the parts including the receiving for gathering conveyer to initial position

and therefore serving as a substitute for the one-way swinging mechanism of Figs. 1 and 2 and of the walking fluid pressure jack mechanism of Figs. 1 and 2; and

Fig. 9 is an elevational view of the structure shown in Fig. 8 and shows a plurality of ropes for moving the coal splitting tools in dislodging direction together with the gathering conveyer and a single rope for returning the coal splitting tools together with the gathering conveyer to initial position.

Referring to Figs. 1 and 2 it will be seen that the main frame 28 is mounted on tractor mechanism comprising endless tractor belts 29 and 30 for transporting the mining and loading machine over the mine floor 31 in advance of the track 32. I prefer to use tractor mechanism operatively connected to the motor 33 so as to distribute the weight of the mining and loading machine over a wider area not only to facilitate transportation of the mining and loading machine over the mine floor but also to assist the roof jacks 34 and 35 in more firmly holding the main frame 28 in adjusted position during the mining and loading operations hereinafter described. These roof jacks are preferably pivotally connected to the upper side portions of the frame 28 as shown in Figs. 1 and 2. A wheel 37 screw threaded on the rod 38 may be relied upon to thrust the upper end of said rod against the roof 39.

At the lower portion of the frame 28 is a rearward extension 40 to which is pivoted at 41 the lower side of the hopper 42. This hopper is provided with a rearward extension 43. An endless conveyer 44 is mounted to extend from the bottom of the hopper 42 to the outer open end 45 of the horizontal chute 43. This conveyer 44 may be operated by means of the motor 46.

Connected to the upper rear portion of the frame 28 is a horizontal U-shaped extension 47 at the center of which as indicated at 48 in Figs. 1 and 2 is pivoted the arm 49 which is T-shaped and connected at 50, 50 to the hopper 42 and chute 43. It will thus be seen that the pivotal connections 41 and 48 are in vertical alinement and permit the hopper 42 and the chute 43 and the conveyer 100

44 to be swung laterally so that the delivery end 45 of the conveyer 44 may extend into the mine car 51 on a track 32 or on the track parallel thereto on either side of the track 32.

5   Mounted on the frame 28 is an endless belt conveyor 52 in position to receive material delivered into the hopper 53 and move the same rearwardly and upwardly for delivery into the hopper 42. It should be noted that 10 the hopper 42 is comparatively large and deep with its bottom closed so that it may act temporarily as a storage hopper while the conveyer 52 continues to deliver material to such hopper and the conveyer 44 is out of 15 operation during the removal of a loaded mine car and the bringing up of an empty mine car.

Mounted on the forward end of the frame 28 is a supplemental frame 54 provided with a 20 ring 55 surrounding the lower portion of the hopper 53 and having an annular bearing connection with the frame 28 so as to support the supplemental frame 54 for swinging movements laterally on an upright axis approximately at the center of the hopper 53.

Mounted on the frame 54 and extending radially relative to the upright axis 56 of swinging movement of the frame 54 is a receiving endless conveyor 57 operated by a 30 motor 58. It should be noted that the conveyor 57 swings with the supplemental frame 54 on the axis 56 and is therefore in delivery communication with the hopper 53 through a range of approximately 180 degrees.

On the frame 54 back of the receiving conveyor 57 are mounted a plurality of coal dislodging tools. Tool holders 60 and 61 are provided respectively adjacent to floor and 40 roof of the mine chamber. The tool holder 60 carries the spaced-apart dislodging tools 62 and 63. The tool holder 61 carries similar coal dislodging tools 64 and 65. The upper side of the tool holder 61 carries a coal dislodging tool 66 and the lower tool holder 60 carries a similar dislodging tool 67, as shown in Figs. 3 and 4. The tools, 62, 63, 64 and 65 may be in vertical alinement. The tools 62, 63, 64 and 65 are rigidly connected to the tool 50 holders 60 and 61 as by means of set screws as illustrated at 68 in Fig. 1. It will thus be seen that the tools 62, 63, 64 and 65 constitute spaced-apart fingers in approximate vertical alinement movable with frame 54 along arcuate paths of travel on the upright axis 56 to tear asunder or dislodge the coal, as illustrated in Fig. 1. The fingers 62 and 63 are rigidly connected to the frame 54 and move bodily therewith when the latter is 60 swung on the upright axis 56.

The tool holder 61 is connected to an auxiliary frame 69 to which are rigidly connected the downwardly extending piston rods 70 and 71 extending through the bearing boxes 65 72 and 73 to the pistons in the vertical cyl-

inders in the frame 54. By means of this mechanism the fingers 64 and 65 may be adjusted in elevation together with the finger 66 and at the same time the tool holder 61 may be rigidly connected to the frame 54 so as to move bodily therewith, particularly when the pistons together with the piston rods 70 and 71 are located a comparatively wide distance apart.

Inasmuch as the frame 54 is so mounted on the frame 28 as to always occupy a position spaced a short distance from the mine floor the fingers 62 and 63 will always remain approximately at their adjusted elevations. It should be understood, however, that the finger 62 may have any desired spacing and may initially be located at varying elevations. In low roof mine chambers the tool holder 61 together with the parts connected thereto including the piston rods 70 and 71 may be entirely omitted and the fingers on the frame 54 relied upon to dislodge the material, particularly when the upper finger is located at an elevation approximately that of the chute 43.

Furthermore, the fingers 62 and 63 may be slightly adjusted in elevation by a floor jack which comprises a piston movable in the cylinder to force the plunger 81 against the floor 31. A similar jack 82 is shown on the tool holder 61 for thrusting the plunger 83 against the roof 84. The primary function of the jacks, however, is to guide the tool holders 60 and 61, respectively, along the floor and roof of the mine chamber so as to hold the dislodging tools 62, 63, 64 and 65 at predetermined distances from the floor and roof.

In order to exert considerable pressure back of the tool holders 60 and 61, I have provided a pair of walking roof jacks 99 and 100. The roof jack 99 comprises a cylinder 101 for receiving a plunger at the upper end of which is a roof plate 103. Likewise the roof jack 100 comprises a cylinder 104 for receiving a plunger at the upper end of which is the roof plate 106.

At the lower portions of the cylinders are annular bearings 107 and 108 for receiving the rings or collars 109 and 110 which are connected to the piston rods 111. The latter are connected to pistons in the cylinders pivotally connected to the tool holder 60, horizontal slots being provided in the tool holder 60 to permit lateral swinging movements of the fluid pressure motors comprising the cylinders 115 and 116 when such fluid pressure motors are operated to move the dislodging tools 62 and 63 into unmoved mass.

Surrounding the plungers so that the latter will be freely slideable therethrough are the rings or collars 119 and 120 which are connected by the piston rods 121 and 122 of the pistons 123 and 124 in the cylinders 125

and 126. The latter are pivotally connected to the tool holder 61 and slots are provided in the tool holder 61 to permit lateral swinging movements of the fluid pressure motors comprising the cylinders 125 and 126 when such fluid pressure motors are operated to actuate the dislodging tools 64 and 65.

It should be understood that the horizontal fluid pressure motors 115, 116 and 125, 126 are also relied upon to alternately move the roof jacks 99 and 100 forwardly to new roof propping positions where such roof jacks will alternately act as anchorages for the fluid pressure motors when acting to thrust forward the dislodging tools, particularly those designated 62, 63, 64 and 65. Each of the fluid pressure motors may be controlled by a set of manually operated valves.

By referring to Fig. 2 it will be seen that the supply pipe 136 is connected to a manifold 145 and a valve 146 is provided in the pipe 136 to control the flow of the pressure medium to the fluid pressure motor. In a similar manner the pipe 139 is connected to the manifold 145 and provided with a controlling valve 147.

The cylinder of the roof jack 99 is connected by a pipe 148 to the manifold 145 and this pipe is provided with a controlling valve 149, an exhaust connection being indicated at 150. Therefore, when the valve 149 is opened the pressure medium going through the pipe 148 into the cylinder will force the plunger 102 into roof engaging position to anchor the roof jack 99. When the valve 149 is opened to the exhaust 150 the plunger 102 will slide through the ring or collar 119 and thus release the plate 103 from the roof. When the roof jack 99 is in released position and the pistons 113 and 123 are moved to the right, as viewed in Fig. 4, the said roof jack 99 is moved forward to a new position whereupon the valve 149 is again manipulated to move the plunger to anchoring position. Immediately after the roof jack 99 has been thus moved forward and again anchored the roof jack 100 is released by opening the valve 151 to exhaust 152 so that the pressure in the cylinder 104 will be relieved and permit the plunger 105 to descend. As soon as this occurs the levers are moved toward the left so as to connect the chambers to the exhausts and so as to connect the supply pipes 136 and 139 to the chambers at the left of the pistons. Since the roof jack 99 is anchored at this time the tool holding frames 61 and 60 will be moved forward to cause the fingers 62, 63, 64 and 65 to penetrate the material at the upright arcuate mine wall and dislodge the material, as indicated in Fig. 1, in position to be received by the conveyer 57 for transfer to the hopper 53 and in turn to be transferred by the conveyer 52 to the deep storage hopper 42 for transfer by the conveyer 44 to the mine car 51.

While the roof jack 99 is in anchored position and the fluid pressure motors connected thereto are operating to move the tool holders 60 and 61 forward arcuately the roof jack 100 should be moved forward to a new position by means of the fluid pressure motors connected thereto, which fluid pressure motors comprise the horizontal cylinders. These fluid pressure motors are connected by pipes 155 and 156 to the manifold 145, the pipe 155 being provided with a valve 157 and the pipe 156 being provided with a valve 158. The pistons in these fluid pressure motors may be moved in one direction or the other by operating the levers, which are connected to similar sets of valves. The throw of each of these levers is approximately 90 degrees.

Inasmuch as the fluid pressure motors also have reciprocating pistons the movements of the latter may be controlled by sets of valves similar to those operated by the above-mentioned lever. To operate the motor the lever moved is one direction or the other to control the pressures on the piston from the supply pipe which is connected to the manifold 145. A supply pipe extends from the manifold to the valves operated by a lever to control the motor. The lever controls the motor by controlling the flow of fluid pressure from a pipe which is also connected to the manifold 145. A lever controls the fluid pressure motor 82 by controlling the pressure from the pipe which may also be connected to the manifold 145. Each of the pipes connected to the manifold may be provided with a single manual valve, those in the pipes connected to the anchoring roof jacks being provided with exhausts, as indicated at 150 and 152.

The manifold 145 is connected by a pipe 170 through a swivel joint 171 to the pipe 172 which is connected to the pump 173 connected to the motor 33. The swivel joint 171 is located at the axis 56, as shown in Fig. 1, so that the manifold 145 and all the pipes connected thereto may be moved bodily along arcuate lines while the pump 173 is being operated by the motor 33 to maintain fluid pressure in the manifold 145 to operate the fluid pressure motors whenever desired.

It should be noted that when the fluid pressure motors connected to the roof anchoring jacks are operated to move the series of coal dislodging tools arcuately along the mine wall on the upright axis 56, such fluid pressure motors will be moved arcuately on the axis of the anchored roof jacks but the collars will permit such movements of the fluid pressure motors relatively to the roof jacks, and such arcuate movements relatively to the tool holders 60 and 61 will be permitted by reason of the pivotal connections, sufficient lateral movement of the fluid pressure motors relatively to the tool holders 60 and 61 being permitted by the horizontal slots.

It should also be noted that while the strokes of the pistons relatively to the cylinders of the horizontal fluid pressure motors connected to the roof jacks are continuous from one end of each cylinder to the other end thereof during the normal operation of the walking roof jacks it is desirable to lock the pistons in the motors in adjusted position and this may be effected by movements of the levers to vertical positions where the passage will be cut off from any of the pipes to which the valves are connected. However, if the pistons are at the ends of the cylinders such locking may be effected by closing the valve adjacent the manifold 145.

As shown in Fig. 3, the receiving conveyer 57 may comprise an endless belt 175 mounted on rollers 176 and 177 and provided with lateral sprocket chains 178 and 179 for engagement by the sprockets 180 and 181 on the transverse shaft 182 connected to the gearing 183 operated by the motor 58. Preferably the endless belt 175 travels upwardly along a chute comprising the vertical side plates 185 and 186 and the bottom plate 187.

The conveyor frame is pivoted at 188 on a horizontal axis on the upper peripheral edge of the hopper 53 so that this receiving conveyor 57 may be moved up and down on the axis 188 independently of the frame 54 in Fig. 1. The outer end of conveyor may rest on the floor and slide over the same or the vertical plate 189 connected to the bottom of the conveyor frame at one side thereof may be relied upon to rest against the ring 55 as shown in the Fig. 6 to hold the conveyor spaced slightly from the floor at the mine wall.

Extending across the front end of the conveyor is a scoop 190 provided with a plurality of spaced-apart slots 191 to receive the teeth 192 of the jigger plate 193 which is located at the floor at the base of the mine wall in position to move the dislodged material on to the conveyor belt 187 as shown in Fig. 6. The horizontal floor plate 193 extends under the scoop 190 and is provided with a rearwardly extending arm 194 mounted on a bracket 195. A spring 196 is connected between the vertical plate 189 and the forward end of the arm 194 to continually urge the plate 193 forward to a position beyond the arcuate face of the mine wall. The conveyor is located ahead of the dislodging mechanism as shown in Fig. 1 and when the plate 193 engages unmined material its forward movement will be stopped, but when the material is dislodged the plate will move under such dislodged material as shown in Fig. 6. However, the plate 193 may have the length of its extended portion varied so as to assure the movement of the dislodged material onto the conveyor 57.

In order to secure a comparatively slow movement of the plate 193 with the material

thereon toward the conveyor there is provided an upwardly extending lever 197 at the rear end of the arm 194 in position to be engaged by the pin 198 extending laterally from the gear 199 as shown in the Figs. 6 and 7. This gear is operatively connected by the pinion 200 to the motor 201 which is mounted on the vertical plate 189. When the pin 198 is rotated it engages the lever 197 to move the arm 194 and the plate 193 rearwardly against the action of the spring 196. The teeth 192 engaging the dislodged material will effect movement of the latter slowly toward the left as viewed in Fig. 6. After the pin 198 has been rotated clock-wise as viewed in Fig. 6 slightly more than 180 degrees the arm 194 will be released and the spring 196 will be free to act to suddenly move the plate 193 forward under any material at the base of the mine wall in the path of the plate.

After a complete semi-circular stroke of the dislodging mechanism has been made from the position of the dotted lines shown in Fig. 1 such dislodging mechanism may be quickly returned to initial position in readiness for another series of dislodging operations, after which the tractor mechanism may be operated to move the entire mining and loading machine to a new forward position. To effect this quick return movement a draft rope 220 is connected to the frame 54 as shown in Figs. 2 and 9 and wound on the drum 221 connected for operation to the motor 222.

When the material to be dislodged is comparatively soft so that fluid pressure motors such as hydraulic motors are not necessary to secure the requisite amount of force to operate the coal dislodging tools the rope winding mechanism illustrated in Figs. 8 and 9 may be used to swing such tools arcuately to cause them to dislodge the material. In this event the walking roof jacks together with the other fluid pressure mechanism may be omitted and the roof jacks 34 and 35 relied upon to hold the main frame 28 in stationary position during the operation of the dislodging mechanism. The rope-winding mechanism illustrated in Figs. 8 and 9 includes the rope-winding drum 221, the motor 222 and the single rope 220 as shown in Figs. 2 and 9, for returning the dislodging mechanism to initial position, but the connections to secure dislodging operation of dislodging tools includes the plurality of ropes 223 connected to the side of the ring 55 opposite the point 224 to which the rope 220 is connected. By means of suitable reduction gearing between the motor 222 and the winding-drum 221 a slow but very powerful turning movement may be exerted on the ring 55 to move the frame 54 together with the dislodging tools mounted thereon arcuately along the mine wall to effect dislodgment of the material as illustrated in Fig. 1. When

the fluid pressure operated walking apparatus is omitted and the rope-winding mechanism used for moving the coal tools in dislodging direction, the upper tools 64 and 65 are rigidly connected through the structure shown 5 in this view to the frame 54 so as to move bodily with the latter.

In Fig. 2, there is diagrammatically illustrated mechanism for lifting and lowering the 10 vertical rack bars to adjust the elevation of the spaced-apart horizontal beams 228 and 229 to adjust the elevation of the kerf-cutting mechanism. This mechanism for lifting and 15 lowering the vertical rack bars comprises a motor 236 connected by a shaft 237 to gearing meshing with such rack bars. A shaft 238 as shown in Fig. 1 extends transversely across the upper portion of the frame 28 a sufficient 20 distance above the conveyor 52 and a sufficient distance to the right of the delivery end thereof to not interfere with the passage of material being transferred from the hopper 53 to the hopper 42. On the opposite side of frame 28 a longitudinal shaft 239 parallel to the shaft 237 transmits power from 25 the transverse shaft 238 to the gearing for operating the vertical racks corresponding to those designated 232 and 233 on the opposite side of the machine. The starting and stopping and the reversal of the electric motor 236 is all that is necessary to regulate the elevation of the parallel bars 228 and 229 and the kerf-cutting machine mounted thereon.

There is shown herein mining mechanism 30 in a combined mining and loading machine to show the particular adaptation of the improved loading apparatus. The mining mechanism and the combined mining and loading apparatus is claimed in the co-pending 35 application, Serial No. 346,903, filed December 23, 1919, whereas the loading apparatus per se is covered by claims in the present application. It should be understood that the kerf-cutting mechanism and the coal dislodging tools may be omitted so that the remaining 40 structure is a simple loading machine. Furthermore, as above explained, the walking roof jacks may be omitted and the rope winding mechanism shown in Figs. 8 and 45 9 relied on to swing the receiving conveyor to gather the material from the floor by means of the scoop 59. Such rope winding mechanism may be sufficient when the material to be loaded is loose on the floor, but when the coal is shot down by blasting it is likely to be dislodged in a semi-compact mass 50 and for loading such dislodged coal it will be desirable to retain the roof jack walking mechanism.

Obviously those skilled in the art may 55 make various changes in the details without departing from the spirit and scope of the invention as defined by the claims here- 60 to appended and the invention is therefore

not to be limited to the precise construction herein disclosed.

Having thus disclosed an embodiment of the invention, what is claimed and desired to be secured by Letters Patent of the United States is:

1. In a loading machine, the combination with a supporting frame, of a gathering conveyer, a plate adapted to reciprocate with advancing and retracting movements under 75 the forward end of said gathering conveyer, means for reciprocating said plate to gather a load of material and deliver the same to said gathering conveyer, and a plurality of spaced-apart upwardly projecting teeth on 80 the forward portion of said reciprocating plate.

2. In loading mechanism, a gathering conveyer having an extensible member at the end thereof for drawing material to said conveyer; motor driven means for causing said extensible member to move toward said conveyer, and resilient means to project said extensible member from the end of said conveyer.

3. In loading mechanism, the combination with a frame, of a gathering conveyer positioned in advance of said frame to rotate in unison therewith, extendible means on the end of said gathering conveyer, a spring to project said extendible means to a position to receive material from the mine wall, and a motor to retract said extendable means when the same is loaded.

4. In loading mechanism, the combination with a supporting frame, of a receiving hopper, a gathering conveyer, framework for rotatably supporting said gathering conveyer on said receiving hopper, a horizontal jigger plate mounted on said framework, a motor mounted in said frame for retracting said jigger plate when material loosened from a mine wall is loaded thereon, means for causing the material on said jigger plate to fall upon said gathering conveyer, and a spring 100 to extend said jigger plate when the same is unloaded.

5. In a loading machine, the combination with a supporting frame, of a gathering conveyer, a plate adapted to reciprocate under the forward end of said conveyer, a plurality of upwardly projecting gripping teeth on the forward edge of said plate, a cross-piece at the lower end of said conveyer adjacent said plate with an upper inclined 105 surface for directing the material from said plate to said conveyer, and means for reciprocating said plate to advance the same for a load and retract the same to deliver such load over such inclined surface to said conveyer.

6. In loading apparatus, the combination with a conveyer adapted to extend to the surface from which the material is to be loaded, of an extensible device at the for- 110

ward end of said conveyer for drawing material to said conveyer, releasable motor driven means for causing said extensible device to move toward said conveyer, and resilient means for automatically extending said device out from said conveyer to gather a load when released from said motor driven means.

7. In loading apparatus, the combination with a conveyer, of a reciprocatory plate under the forward end thereof, a reciprocatory operating arm connected to said plate, a spring tending to move said plate out from the lower end of said conveyer, and a motor operated rotary actuating device for engaging said arm over a path of approximately 180° to move said plate toward said conveyer to deliver material on said plate to said conveyer, and then automatically releasing said arm to permit said spring to move said plate out from the said conveyer to gather another load.

Signed at New York, county of New York, and State of New York, this 22nd day of January, 1925.

OLIVE EUGENIE MORGAN,
Executrix of the Estate of Edmund C. Morgan, deceased.
